UNITED STATES PATENT OFFICE.

HENRY B. SARGENT, OF NEW HAVEN, CONNECTICUT, ASSIGNOR TO SARGENT & COMPANY, OF NEW HAVEN, CONNECTICUT, A CORPORATION OF CONNECTICUT.

DOOR-HOLDER.

SPECIFICATION forming part of Letters Patent No. 788,950, dated May 2, 1905.

Application filed January 16, 1904. Serial No. 189,314.

To all whom it may concern:

Be it known that I, HENRY B. SARGENT, of the city and county of New Haven, State of Connecticut, have invented a new and useful Improvement in Door-Holders, of which the following is a full, clear, and exact description when taken in connection with the accompanying drawings, which form a part thereof, and in which—

10 Figure 1 represents a front elevation of a door-holder embodying my invention; Fig. 2, a rear view of the same; Fig. 3, a longitudinal section on lines 3 3 of Fig. 1; Fig. 4, a similar view with the plunger shown in its protracted position; and Figs. 5 and 6, detailed views, in front and side elevation, of the clamp.

In all figures similar letters of reference represent like parts.

This invention relates to door-holders; and 20 it consists in the utilization in a door-bolt of an angular clamp one end of which is rigidly secured to the casing and the other end of which is adapted to bind on the plunger of the bolt to limit its longitudinal movement.

25 Hitherto where clamps have been employed in holders of this character the clamps have been fulcrumed in the casing, and an additional spring or springs are necessary to hold the clamp in its normal position, and these 30 springs are often broken or lose their tension.

The object of this invention is the production of a novel and efficient holder having a minimum of parts by the employment of a clamp of this character without the use of 35 springs and having the various improvements and combinations of parts set forth and claimed hereinafter.

Referring to the drawings for a more particular description, the parts designated by 40 the letter A represent the casing of the holder, which is adapted to be secured to a door or other object by means of screws through screw-holes *a* or by other suitable means.

B is the plunger, herein shown as a rod, extending upward through an opening *a'* in the 45 top of the casing and having a foot-plate *b* at its upper end. Its lower end is yieldingly connected in well-known manner to a cylindrical socket *b'*, carrying a rubber tip *b''*.

C is a plate rigidly mounted on the plunger 50 B, and D is a coiled spring surrounding the plunger and having one end bear on the plate C and its other end on an internal flange *a''* in the casing A.

E is a clamp formed of an angular plate of 55 steel or other suitable material, having its upper end secured to the casing A by rivet *e* or in other manner. The lower portion of said clamp E is provided with a perforation F, slightly larger than the diameter of 60 the plunger B, and through this perforation F the plunger is adapted to project, as shown particularly in Figs. 3 and 4. The end G of the lower portion of the clamp extends through a slot *a''* in the front of the casing A and forms 65 a convenient instrumentality for operating the clamp. When the clamp is in its normal position, its lower portion lies in a position somewhat off the perpendicular to the plunger, and therefore the edges of the perforation 70 F bind on the plunger B and prevent its longitudinal movement therein; but when downward pressure is brought to bear on this portion either on the projecting end G of the clamp E or through the plunger B, owing to 75 the flexibility of the clamp, it is swung to a position more nearly perpendicular where the edges of the perforation F do not bind on the plunger B, so that the plunger is free to move longitudinally through the perforation. On 80 the other hand, any upward pressure on the plunger and through it on the lower portion of the clamp will throw it still further from the perpendicular and cause the clamp to bind still more effectively.

85 The operation of the device is as follows: When it is desired to operate the holder, power is applied to the plate *b* of the plunger, and the plunger is forced downward against the tension of the spring D as the clamp is swung 90 away from its normal position by the downward pressure exerted on the plunger. The rubber tip then bears on the floor or other object to hold the door in the desired position. To retract the plunger, it is only necessary to 95 exert pressure on the projecting end G to swing the clamp so that the edges of the perforation F will not bind on the plunger, when

the spring D will cause the plunger and associated parts to fly back to their normal position.

Having now described my invention, what I claim, and desire to secure by Letters Patent, is—

In a door-holder, the combination with a casing; of a plunger capable of longitudinal movement therein; a spring normally holding said plunger against protraction; means for protracting said plunger against the tension of said spring; and a clamp of angular form, one part of which is formed of resilient ma-

terial and has one end rigidly secured to said casing, and the other part of which extends substantially at right angles to said plunger, and is provided with a perforation through which said plunger projects, so that said clamp will normally bind on said plunger to prevent its retraction, substantially as described. 20

In witness whereof I have hereunto set my hand on the 13th day of January, 1904.

HENRY B. SARGENT.
